WALTER L. HODEAUX, OF PALM BEACH, FLORIDA

ELECTRIC SWITCH FOR POWER TOOLS

Application filed December 22, 1930. Serial No. 504,125.

This invention relates to an electric switch and more particularly to a switch mounted in the handle of a power tool driven by an electric motor. One object of the invention is to so construct the switch and so mount the same in the handle that the operator of the tool may close the switch by pressing a thumb of the hand upon a plunger forming part of the switch and projecting from the grip of the handle.

Another object of the invention is to provide a switch of such construction that when the plunger is pressed inwardly to close the switch, a latch will be moved to an operative position by the plunger, thereby releasably securing the switch in a closed position and making it unnecessary for the operator to exert sufficient pressure upon the plunger to retain the switch closed.

Another object of the invention is to so associate the plunger with a rod forming part of the switch that when the operator's thumb is removed from the plunger, the plunger may move outwardly, thereby permitting the latch to move to a releasing position so that the rod may shift longitudinally to an extended position and open the switch.

Another object of the invention is to provide a switch which is simple in construction and very easy to operate, and further to so construct the switch that it may be very easily mounted in the grip of the tool handle.

The invention is illustrated in the accompanying drawings, wherein

Fig. 1 is a side elevation showing a power tool provided with a handle having the improved switch mounted in its grip;

Fig. 2 is an enlarged view showing the handle in side elevation;

Fig. 3 is a longitudinal sectional view through the handle with the switch in a closed position;

Fig. 4 is a view similar to Fig. 3 showing the switch open; and

Fig. 5 is a transverse sectional view through the handle taken along the line 5—5 of Fig. 3.

The tool indicated in general by the numeral (1) represents a power tool which may be of any desired specific construction and includes a casing (2) for housing an electric

motor by means of which the tool is driven. A handle (3) is provided at the rear end of the motor housing and includes arms (4) and (5) which at their rear ends support a grip (6) to be grasped by the operator using the tool.

In order to control the motor mounted in the housing (2) there has been provided a switch mounted in a pocket (7) formed in the grip (6). Therefore the grip not only serves its usual function as a grip but also constitutes a switch casing. The pocket (7) of the casing or grip is open along one side and this open side of the pocket is normally closed by a plate (8) which is securely but releasably held in place by screws (9). By this arrangement the plate will be securely held in closing relation to the open side of the pocket (7) but may be easily removed when necessary.

The hand grip 6 at one end of the pocket is formed with an opening (10) and at its other end the grip or casing is formed with a passage (11) through which power wires (12) enter the pocket and with a side opening (13) through which the power wires leave the casing. This side opening communicates with one end of a groove or seat (14) formed in the inner surface of the arm (4) and by referring to Figures 3, 4, and 5, it will be seen that the groove (14) is extended through the sleeve (15) at the front of the handle so that the wires may extend into the motor housing for connection with a motor in the usual manner.

The switch mechanism mounted in the pocket (7) of the grip or casing (6) includes a block (16) formed of insulating material and firmly but releasably secured against a permanent side wall of the casing by screws (17). Contact strips (18) which are preferably formed of resilient metal are secured against opposite side faces of the block (16) by terminal screws (19) to which the power wires (12) are secured and it will be readily understood that until the contacts are bridged, the circuit through the motor will be broken, but as soon as these contacts are bridged, the circuit will be completed and the motor set in operation.

In order to control the switch, there has been provided a rod (20) which extends longitudinally of the pocket with one end portion slideable through a bore (21) formed longitudinally through the block of insulating material (16). This bore is enlarged for a portion of its length, thereby defining a spring seat or housing (22) in which is disposed a spring (23). This spring bears against the inner end of a sleeve (24) which fits about the rod (20) and is firmly secured in a set position thereon by a pin (25) the inner or projecting end of the sleeve being provided with an inclined or cam surface 24'; as shown. A collar (26) constituting a bridge for the contacts (18) fits about the sleeve and since the spring normally urges the rod towards the position shown in Figure 4, the bridge will be yieldably held in the position shown in this figure and the circuit will be broken as the bridge is out of engagement with the contacts. By pressing the rod longitudinally to the position shown in Figure 3 in opposition to action of the spring 25 (23), the collar will be moved into tight wedging engagement with the opposed contacts and a very good bridging action will take place. Therefore current may pass through the motor as long as the bridge is in engagement with the free end portions of the contacts which project from one end of the insulating block.

In order to move the rod from the extended or open position shown in Figure 4 to the retracted or closed position shown in Figure 3, there has been provided a plunger (27) which is slidably mounted in the opening (10) formed in the head of the pocket (7) at one end thereof. This plunger, which is 40 of insulating material, is formed hollow in order to slidably receive the outer portion of the rod (20) and the outer end of the plunger is closed by a plug (28) formed with a recess or seat (29) leading from its inner end and 45 slidably receiving the outer end of the rod. Since the seat (29) is closed at its end, inward movement of the plunger will cause the rod to be shifted longitudinally to a retracted position and the bridge or collar will be 50 moved into engagement with the free ends of the contacts. An abutment (30) is formed about the rod (20) within the plunger and between this abutment and the inner end of the plug (28) is disposed a spring (31) which 55 yieldably resists inward movement of the plunger relative to the rod and acts as a cushion to relieve strain when the plunger is pressed inwardly by the operator's thumb.

When the plunger is pressed inwardly to shift the rod longitudinally to a switch closing position it is desired to have the rod secured in the retracted position. I have therefore provided a latch (32) which is pivotally mounted intermediate its ends in the pocket (7) as shown at (33). The handle

(34) of the latch extends across a pin (35) which limits its swinging movement in one direction as shown in Figure 3 and this handle is provided with a downwardly inclined terminal lip 34' normally engaged by a spring (36) which urges the latch towards the position shown in Figure 4, but will permit such latch to be moved to the operative position shown in Figure 3 for engagement with the tapered outer end of the sleeve (24). The free end portion of the handle is held in engagement with the plunger (27) and since the inner end portion (37) of this plunger is tapered it forms a cam which will act upon the handle to swing the latch towards an operative position when the plunger is pressed inwardly.

During use of the tool the operator grasps the grip of the handle with one hand with the thumb of this hand resting upon the outer end of the plunger. When it is desired to start the motor in order to operate the tool, pressure is applied to the plunger in order to press the plunger inwardly. As the plunger is pressed inwardly, the rod (20) is shifted longitudinally towards the position shown in Figure 3 and during inward movement of the plunger the tapered inner end thereof causes the latch to be swung towards the operative position. By the time the plunger has been shifted inwardly a sufficient distance against the action of the spring (23) to move the collar or bridge (26) into wedging engagement with the free end portions of the contacts (18), the bill of the latch will have moved into engagement with the outer or inclined end of the sleeve (24), and since the handle now bears against a side of the plunger beyond the tapered inner end thereof, the latch will be held in operative engagement with the inclined end of the sleeve and the rod cannot move outwardly towards an open position. Therefore, it is not necessary for the operator to exert excessive pressure upon the plunger in order to retain the switch closed. Inward movement of the plunger also compresses the spring (31) and as soon as it is desired to shut off the motor, it is merely necessary to move the thumb outwardly and the spring (31) will shift the plunger outwardly a sufficient distance to permit the plunger to return to the position shown in Figure 4.

When this takes place the spring (36) acts against the handle of the latch to move the latch towards a releasing or inoperative position and since the outer end of the sleeve is tapered, movement of the latch towards the releasing position will not be interfered with by frictional engagement between the latch and the outer end of the sleeve. As soon as the latch is moved out of engagement with the outer end of the sleeve, the spring (23) may then expand and shift the sleeve and rod longitudinally towards the position

shown in Figure 4. Therefore the collar or bridge will be moved out of engagement with the contacts and the circuit will be broken. Since the spring (23) is quite strong, movement of the rod towards the opened position will take place very rapidly and arcing will be prevented.

What is claimed is:

1. A switch for power tools comprising contacts insulated from each other, a rod 10 slideable longitudinally between said contacts, a sleeve carried by the rod, a collar on the sleeve adapted to bridge the contacts when the rod is moved to circuit-closing position, means yieldably holding the rod in extended position, an actuating member for the rod movable relative thereto, a cushion between the rod and actuating member, and a spring-pressed latch pivoted intermediate its ends and having one end thereof disposed in the path of and adapted to be engaged by said actuating member for moving the other end of the latch in engagement with the sleeve thereby to hold the rod in circuit-closing position when said actuating member is pressed inwardly.

2. A switch for power tools comprising contacts insulated from each other, a rod 30 slideable longitudinally between the contacts, a sleeve carried by the rod and having a cam face, a collar adapted to bridge the contacts when the rod is moved to circuit-closing position, means yieldably holding the rod in extended position, an actuating member for the rod movable relative thereto and having a cam face, a cushion between the rod and actuating member, and a spring-pressed latch pivoted intermediate its ends and having one end thereof disposed in the path of and adapted to be engaged by the cam face of said actuating member for moving the other end of the latch in engagement with the cam face of the sleeve thereby to hold the rod in circuit-closing position when 40 the actuating member is pressed inwardly.

3. A switch for power tools comprising contacts insulated from each other, a rod 50 slideable longitudinally between said contacts, a sleeve carried by the rod and having one end thereof beveled to form a cam face, a collar on the sleeve adapted to bridge the contacts when the rod is moved to circuit-closing position, means yieldably holding the rod in extended position, an actuating member for the rod movable relative thereto and having its inner end provided with a cam face, a cushion between said rod and actuating member, a latch pivoted intermediate its ends and having one end thereof provided 60 with an inclined lip disposed in the path of and adapted to be engaged by the cam face of the actuating member for moving the other end of the latch in engagement with the sleeve to hold the rod in circuit-closing position 70 when said actuating member is pressed in-

wardly, and means for automatically releasing the latch when the actuating member is moved to extended position.

4. A switch for power tools comprising contacts insulated from each other, a rod 70 slideably mounted between said contacts, a sleeve carried by the rod and provided with a cam face, a collar adapted to bridge the contacts when the rod is moved to circuit-closing position, means yieldably holding the rod in extended position, an actuating member 75 for the rod movable relative thereto and provided with a cam face, a cushion between the rod and actuating member, a pivoted latch having one end thereof provided with a bill and its other end formed with a handle, means for limiting the pivotal movement of the latch, the handle of the latch being disposed in the path of and adapted to be engaged by the cam face of the actuating member 80 for moving the bill of the latch into engagement with the sleeve cam to hold the rod in circuit-closing position when the actuating member is pressed inwardly, and means for disengaging the bill of the latch 85 from the cam face of the sleeve when the actuating member is moved to extended position.

5. A switch for power tools comprising a 90 block of insulating material having a bore, spring contacts secured to the block, a rod slideable longitudinally through the bore of the block, a sleeve carried by the rod and provided with a cam face, a collar secured to the sleeve adapted to bridge the contacts when the rod is moved to circuit-closing position, a spring disposed within the bore and bearing against the sleeve for holding the rod in extended position, an actuating member 95 for the rod movable relative thereto and provided with a cam face, said actuating member being hollow to permit insertion of the rod, a spring disposed within the actuating member and surrounding the rod, a latch 100 pivotally mounted intermediate its ends, a transverse pin for limiting the pivotal movement of the latch, one end of the latch being provided with a bill adapted to engage the cam face of the sleeve to hold the rod in circuit-closing position and the other end of the latch being provided with a terminal inclined lip coacting with the cam face of the actuating member, and a spring bearing against the lip of the latch for normally holding the bill of said latch out of engagement with the cam face of the sleeve.

In testimony whereof I affix my signature.
